(57) **CLAIM**

The ornamental design for a roll-over protection structure having diamond frame with multi-angle bend, as shown and described.

DESCRIPTION

FIG. 1 is a rear perspective view of a roll-over protection structure having diamond frame with multi-angle bend embodying our design and being depicted as part of a riding mower for environmental purposes, with the mower, the lower frame section, and the hinge assembly being shown in broken lines for illustrative purposes only and forming no part of the claimed design;

FIG. 2 is an enlarged rear perspective view of the roll-over protection structure shown in FIG. 1, but with the mower being removed;

FIG. 3 is an enlarged front perspective view of the roll-over protection structure as depicted in FIG. 2;

FIG. 4 is a rear elevation view of the roll-over protection structure shown in FIGS. 1-3, but with the lower frame section and hinge assembly being wholly removed such that only the upper frame section is shown;

FIG. 5 is a top elevation view of the roll-over protection structure as depicted in FIG. 4;

FIG. 6 is a front elevation view of the roll-over protection structure as depicted shown in FIGS. 4 and 5;

FIG. 7 is a bottom elevation view of the roll-over protection structure as depicted in FIGS. 4-6; and,

FIG. 8 is a left side elevation view of the roll-over protection structure as depicted in FIGS. 4-7, with the right side elevation view being a mirror image thereof.

The broken line showing the riding mower is provided for the purposes of illustrating environmental structure while all other broken lines illustrate portions of the roll-over protection structure. No subject matter shown in broken lines form part of the claimed design.

1 Claim, 5 Drawing Sheets
